PANTY CONSTRUCTION
Bernice J. Mann, R.D. 1, Hornell, N.Y.
Filed Jan. 25, 1961, Ser. No. 84,849
5 Claims. (Cl. 123—284)

This invention generally relates to a garment and more particularly to that type of panty incorporating a diaper used for babies in which the panty incorporates a removable diaper which is easily positioned and replaced for expediting the changing of diapers, laundering of the garment and generally facilitating proper care for the child.

The primary object of the present invention is to provide an improved type of panty which may be employed as a diaper holder or employed as a training panty after the child has passed the stage of diaper use, and, further, to provide means for detachable engagement with a blouse type of garment, such as a shirt or the like, for retaining the panty in the desired position and for retaining the shirt in the desired position.

A further object of the present invention is to provide a panty construction incorporating a construction which may be employed in conjunction with triple thickness diapers for small children, single thickness diapers of material which may be employed with doll babies, and also a diaper of disposable material, all of which employ the same inventive concept and all of which employ a panty of substantially hour-glass construction for fitting a child or doll baby.

Other objects of the present invention will reside in its simplicity of construction, ease of assembly on an infant, ease of assembly of the diaper thereon, and its relatively inexpensive manufacturing cost.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a perspective view of the panty construction of the present invention;

FIGURE 2 is a vertical sectional view taken substantially upon a plane passing along section line 2—2 of FIGURE 1 illustrating the details of construction thereof;

FIGURE 3 is a plan view of the panty illustrating the construction of the elastic members on each end thereof;

FIGURE 4 is a detailed sectional view taken substantially upon a plane passing along section line 4—4 of FIGURE 2 illustrating the manner of attaching the snap fastener elements to the present invention;

FIGURE 5 is a plan view of the diaper employed in this invention;

FIGURE 6 is a plan view of a modified form of panty construction adapted for use with infants;

FIGURE 7 is a plan view of the triple thickness diaper constructed for use in the device of FIGURE 6;

FIGURE 8 is a plan schematic view of another form of the invention in which a disposable diaper is employed;

FIGURE 9 is a plan view of another panty construction in which the entire panty is made of knit cloth only; and

FIGURE 10 is a schematic view of a shirt type garment which may be employed with the panty construction of the present invention.

Referring now specifically to FIGURES 1—5 of the official drawings, the numeral 10 generally designates the panty construction of the present invention, which includes a main body panel generally designated by the numeral 12 which is substantially in the shape of an hour-glass having concave portions 14 and convex portions 16 on the side edges thereof and parallel end edges 18. In-

2

wardly extending, triangular darts 20 may be provided on the convex edge portions 16 for permitting the panel 12 to more nearly fit the device upon which the panty can be mounted.

5 The body panel 12 is constructed of an outer layer of fabric material designated by the numeral 22 and an inner layer of waterproof material designated by the numeral 24 which may be suitable plastic or the like.

Adjacent each end edge 18 is an elongated elastic strap member 26, with each elastic strap member 26 having a snap fastener element 28 at each end thereof wherein the snap fastener elements 28 may be secured to each other in waist encircling relation for mounting the panty 10 in position. Also provided on each elastic member 15 26 is a pair of spaced snap fastener elements 30 disposed inwardly of the snap fastener elements 28 for engagement with similar snap fastener elements 32 on a rectangular diaper member 34 which is of single thickness and is disposed against the inner surface of the panel 12 with 20 the snap fastener elements 32 detachably mounting the diaper 34 in position. The elastic member 26 adjacent the long end edge 18 may also be provided with extra snap fastener elements 36 which may be employed for adjusting the effective length of the waist portion of the 25 panty 10 or for engagement with snap fastener elements on a shirt or garment as described hereinafter.

Referring now specifically to FIGURES 6 and 7 of the drawings, the numeral 40 designates a modified form of the panty construction of the present invention, including 30 an hour-glass panel 42 having an outer layer 44 of cloth and an inner layer 46 of waterproof plastic material. End elastic strap members 48 are provided adjacent each end of the body 42 and short elastic strap members 50 are disposed adjacent each concave edge portion 52 of the 35 body panel 42 for more nearly conforming the side edges to the contours of the body of the child for rendering the panty construction more waterproof and to prevent any possible leakage from the panty 40. Darts 54 are provided for permitting the panel 42 to conform to the shape 40 and size of the wearer.

Each of the elastic strap members 48 is provided with snap fastener elements 56 on the outer ends thereof and aligned pairs of snap fastener elements 58 disposed inwardly thereof, with the elongated strap member 48 having 45 an extra pair of snap fastener elements 60 for a purpose described hereinafter.

An enlarged, rectangular diaper 62 is provided and is provided with spaced parallel fold lines 64 so that the diaper 62 may be folded into triple thickness. A snap fastener element 66 is disposed adjacent each fold line 64, so that when the diaper 62 is folded into triple thickness, the snap fastener elements 66 will be disposed at the corners thereof for engagement with the snap fastener elements 58 on the elastic strap members 48. Thus, the 55 triple thickness diaper 62 secured to the inner face of the body panel 42 will effectively absorb all liquid excrement of a small child. The darts 54 and the small elastic members 50 will conform the panty 40 to the child, thus preventing any possible leakage.

60 Referring now specifically to FIGURE 9, a modified form of the present invention is designated by the numeral 70, which includes a main body panel of hour-glass shape designated by the numeral 72 which may be of knit cloth and provided with a knit ribbing 74 on the side edges thereof and elastic strap members 76 adjacent each end edge thereof, with the elastic strap members 76 being identical to those designated by the numeral 48 in connection with FIGURE 6.

70 This form of the invention may also be employed with the diaper member 62 illustrated in FIGURE 7 with the snap fastener elements 66 on the diaper 62 cooperating

with the snap fastener elements on the elastic strap member 76 in the same manner as the snap fastener elements on the elastic strap members 48.

FIGURE 8 illustrates schematically the form of the invention in which a disposable diaper 78 may be employed and inserted under elastic strap members 80 and 82. When the disposable diaper 78 is employed, the snap fastener elements inwardly of the ends of the elastic strap members may be omitted and only the snap fastener elements 84 provided on the ends of the elastic members 80 and 82 for detachable engagement for retaining the diaper body panel (not shown in this instance) in waist encircling position.

FIGURE 10 illustrates a garment of the shirt type generally designated by the numeral 86 which includes a pair of depending pads 88 having snap fastener elements mounted on the lower ends thereof for engagement with the snap fastener elements 60 on the elastic strap members 48 in FIGURE 6 or with the snap fastener elements 36 on the elastic strap members 26 of FIGURE 20 3, thus holding the shirt type garment 86 down and holding the panties up in the desired position.

In connection with the device as illustrated in FIGURE 9, the knit type panty 70 may be employed in the same manner as the waterproof types when the diapers are being employed and may also be employed as a training panty after the diaper stage is passed.

FIGURE 4 illustrates the details of mounting the snap fastener elements onto the main body panel 12, and it is pointed out that in each instance the snap fastener elements are provided with rounded outer surfaces as designated by the numeral 92, thus preventing any injury to the child using the device.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope 40 of the invention as claimed.

What is claimed as new is as follows:

1. A panty construction comprising a body member generally hour-glass in shape and having parallel end edges, said body member including a panel of fabric material, and a lining of waterproof material, an elastic member attached to the inner surface of the body member throughout the length thereof adjacent each end edge thereof, means for detachably connecting the ends of the respective elastic members together in waist encircling relation, and a generally rectangular diaper having the ends thereof detachably connected to the elastic members adjacent the outer ends thereof and being otherwise free of the body member, said diaper being constructed of absorbent material.

2. A panty construction comprising a body member generally hour-glass in shape and having parallel end edges, said body member including a panel of fabric material and a lining of waterproof material, an elastic member attached to the inner surface of the body member throughout the length thereof adjacent each end edge thereof, means for detachably connecting the ends of the respective elastic members together in waist encircling relation, and a generally rectangular diaper having the ends thereof detachably connected to the elastic members adjacent the outer ends thereof and being otherwise free of the body member, said diaper

being constructed of absorbent material, said diaper being formed from an enlarged rectangular member folded along parallel fold lines spaced equally from each other and the side edges thereof, thus forming a diaper of triple thickness for use with babies.

5 3. A panty construction comprising a body member generally hour-glass in shape and having parallel end edges, said body member including a panel of fabric material, an elastic member attached to the inner surface of the body member throughout the length thereof adjacent each end edge thereof, means for detachably connecting the ends of the respective elastic members together in waist encircling relation, and a generally rectangular diaper having the ends thereof detachably connected to the elastic members adjacent the outer ends thereof and being otherwise free of the body member, said diaper being constructed of absorbent material, said diaper having snap fastener elements at each corner thereof for detachable engagement with snap fastener elements on the elastic members.

10 4. A panty construction comprising a body member generally hour-glass in shape and having parallel end edges, said body member including a panel of fabric material, an elastic member attached to the inner surface of the body member throughout the length thereof adjacent each end edge thereof, means for detachably connecting the ends of the respective elastic members together in waist encircling relation, and a generally rectangular diaper having the ends thereof detachably connected to the elastic members adjacent the outer ends thereof and being otherwise free of the body member, said diaper being constructed of absorbent material, said diaper having snap fastener elements at each corner thereof for detachable engagement with snap fastener elements on the elastic members, the snap fastener elements on the elastic member having mounting means extending through the elastic member and panel of fabric material for retaining the elements of the panty in assembled and properly orientated position, all of said snap fastener elements presenting rounded surfaces to the outer and inner surfaces of the panty.

15 5. A panty construction comprising a body member generally hour-glass in shape and having parallel end edges, said body member including a panel of fabric material, and a lining of waterproof material, an elastic member attached to the inner surface of the body member throughout the length thereof adjacent each end edge thereof, means for detachably connecting the ends of the respective elastic members together in waist encircling relation, and a generally rectangular diaper having the ends thereof detachably connected to the elastic members adjacent the outer ends thereof and being otherwise free of the body member, said diaper being constructed of absorbent material, said elastic members having mating snap fastener elements thereon with one elastic member having a plurality of elements for permitting adjustment in size whereby the snap fastener elements not in use may be engaged with snap fastener elements on a blouse type garment, thus holding the panty in optimum position.
